UNITED STATES PATENT OFFICE

HERBERT E. MARKS, OF SEWICKLEY, PENNSYLVANIA, ASSIGNOR TO UNITED STATES GYPSUM COMPANY, OF CHICAGO, ILLINOIS, A CORPORATION OF ILLINOIS

SLAB FLOOR OR ROOF CONSTRUCTION

Application filed May 14, 1928. Serial No. 277,425.

The invention relates to slab floors or roofs of the type used in fireproof apartments, hotels, office buildings, factories, and the like, in which slabs rest upon the tops of floor beams or roof purlins hereinafter referred to collectively as beams.

In floors and roofs of this type considerable difficulty has been encountered by reason of the relatively small bearings afforded by the tops of the beams for the ends of the slabs. The tops of the beams are so small that, even when the slabs are of exact size and the beams accurately positioned and straight from end to end, there is no excess bearing surface for the ends of the slabs. But these conditions do not prevail in practice. Not infrequently the slabs are of irregular size, the beams are not accurately positioned, and they are not straight from end to end. Under these practical conditions inadequate bearing support is afforded for the ends of many slabs.

The object of this invention is to provide a floor or roof of the type described in which provision is made for adequately supporting all of the slabs regardless of the customary irregularities met in practice, and also to provide a floor or roof of this type in which the slabs may be connected to each other to form a continuous structure, and in which the slabs may be connected to their supporting beams to tie the latter together.

The invention is illustrated in the accompanying drawings, of which Fig. 1 is a top plan view of a portion of a slab floor or roof; Figs. 2 and 3 vertical sectional views taken on the lines II—II, and III—III, respectively, Fig. 1; Fig. 4 a plan, and Fig. 5 an end view of a modified form of floor or roof slab; Fig. 6 a plan, and Fig. 7 a side elevation, of another modified form of floor or roof slab; and Fig. 8 a transverse sectional view of the slab of Figs. 6 and 7, the plane of view being indicated by the line VIII—VIII, Fig. 6.

In the practice of this invention a floor or ceiling is formed of pre-formed slabs which extend between spaced beams and which are provided with longitudinally extending bars having their ends projecting beyond the ends of the slabs and resting upon the tops of the

beams for supporting the slabs and the loads which they carry. The slabs are so constructed or arranged on the beams that the projecting ends of the bars of the slab in one bay are offset with relation to those of adjacent bays, rendering the full width of the top flanges of the beams available for supporting each slab. The projecting ends of the bars may be, and preferably are, connected to the tops of the beams to tie them together and thus avoid the necessity of providing special tie rods between the beams. In the space above the tops of the beams and between the adjacent ends of the slabs filler bodies of cementitious material are poured, suitable filler-retaining members being preferably provided over the tops of the beams for bridging the gaps between the ends of the slabs and thus afford forms.

Having reference particularly to Figs. 1, 2 and 3, a pair of beams 1 in the form of I-beams are shown in the spaced relationship which ordinarily prevails in roofs and floors. Extending between the beams there are pre-formed slabs 2 of cementitious material, such as concrete, gypsum and the like, the slabs having molded in them at their sides vertically disposed bars in the form of channels 3, the ends of which project beyond the ends of the slabs and rest upon the top flanges of the beams. As shown in Fig. 1, the slabs of one bay are offset with relation to those of an adjacent bay so that the projecting ends of bars 3 have full bearings upon the upper flanges of beams 1. The projecting ends of bars 3 are preferably connected to the beams, this being conveniently done by welding the bottoms of the bars to the tops of the beams as indicated at 4 in Fig. 1, the right-hand portion of which shows the top flanges of channels 3 as being broken away to show the welded connections. By thus or otherwise connecting the bars to the beams, there is eliminated the necessity of providing the customary tie rods between the beams. As shown particularly in Fig. 3, the slab-supporting bars are preferably molded in the sides of the slabs. When so positioned, they afford side facings for the slabs which protect the edges of the slabs against being

chipped off in shipping or handling. The bars of each slab are preferably anchored in the slab by means of strips 5 extending transversely of the slab and having their ends welded or otherwise connected to the bars. As shown in Fig. 3, a very simple and sturdy construction is obtained by welding the ends of the strips 5 to the lower flanges of the channels 3, thus positioning this reinforcement in the lower part of the slab where it has been found to afford the greatest amount of reinforcement value. These strips preferably support and position the reinforcing material in the slab, which material may be in the form of woven or welded wire fabric 6. Below the lower edges of bars 3 the cementitious body material of each slab preferably projects outwardly so that when the slabs are arranged upon the beams troughs are formed between the slabs, the troughs being filled with bodies 7 of the cementitious material.

When the slabs are arranged on the tops of beams 1, there are spaces between the adjacent ends of the slabs above the tops of the beams, in which spaces fills of cementitious material are placed. To prevent these fills from flowing downwardly between the ends of the slabs and the adjacent edges of the upper flanges of the beams, there are provided filler-retaining members 8 (Fig. 2) which preferably extend from the top flanges of the beams, downwardly at their edges and horizontally beneath the bottoms of the slabs. The filler-retaining members may be formed of thin metal, but are preferably formed of cardboard which may be readily molded or otherwise formed to the desired shape.

In Figs. 4 and 5 there is shown a modified form of slab in which slab-supporting channel bars 10 extend from the top to the bottom of the slab thereby facing the sides of the slab throughout its full depth or thickness. These bars have inwardly extending flanges preferably extending flush with the upper surface of the slab, and the back faces of the webs are smooth so that adjoining webs of the channel bars can fit closely together. The bars are preferably anchored in the slab by means of strips 11 having their ends bent for attachment to the inner faces of the bars intermediate said flanges. The slab is shown as being provided with reinforcing material 12, the ends of which project beyond the cementitious bodies of the slab to anchor the fills on the tops of the floor beams, and also to form a suitable means for connecting the adjacent ends of slabs to each other and thereby strengthen the complete floor or roof. With this type of construction, the channel bars 10 are arranged to have the backs of their webs arranged in closely abutting relations so that little or no grouting material 7 is needed between said channel bars and the lower, trough-forming flanges on the slabs

are eliminated, thus making a more simple slab molding operation.

In Figs. 6, 7, and 8 there is illustrated a further modified form of slab in which the slab-supporting bars are in the form of longitudinally extending flats 15 entirely enclosed in the cementitious material. These bars may be anchored in the cementitious material by rods 16 extending transversely of the slab and through perforations provided in the bars. It will be understood that, if desired, any of the forms of slabs may have their bodies of cementitious material extending above the plane of the tops of their bars. To prevent such relative deflection as there may be between the sides of adjacent slabs, their sides may be provided with registering pockets 17 for receiving dowel pins or the like.

In forming a floor or roof of the type herein provided, the filler-retaining members 8 are first placed upon the tops of beams 1, and thereafter the slabs are arranged on the tops of the filler-retaining members in the general offset relationship shown in Fig. 1 so that the projecting ends of the slab bars have full bearing upon the tops of the beams. The projecting ends of the bars may then be connected to the beams as indicated at 4 in Fig. 1, and if the slabs are provided with reinforcements which extend beyond the ends of the slabs, as shown at 12 in Fig. 4, the projecting reinforcements may be connected to each other. Furthermore, in the assembling of the slabs upon the beams dowel pins may be inserted in the pockets 17 (Figs. 6 and 7) to prevent relative vertical deflection between the slabs. Thereafter, fills of cementitious material are poured between the adjacent ends of the slabs above the beams, and also between the adjacent sides of the slabs when the slabs are of the form illustrated in Figs. 1, 2 and 3. The floor or roof structure so formed may then be surfaced with wearing material, waterproofing, and the like depending upon the requirements of service. The projecting ends of the slab bars have full bearings upon the tops of the beams and afford supports for the slabs and the loads which they carry.

By reason of the full bearings thus provided, the slabs are adequately supported regardless of such irregularity in their sizes and in the positions of the beams as prevail in practice. When formed of gypsum, as is preferred, plates, boards or sheets of heat insulating or water-proofing material may be nailed directly to the upper or lower, or both faces of the slabs.

According to the provisions of the patent statutes, I have explained the principle and operation of my invention and have illustrated several embodiments of it. However, I desire to have it understood that, within the scope of the appended claims, the inven-

tion may be practiced by other forms of construction than those specifically illustrated and described.

I claim as my invention:

- 5 1. A slab floor or roof, comprising a plurality of spaced beams, preformed slabs extending between said beams and provided with longitudinally extending bars having their ends projecting beyond the ends of the 10 slabs and resting upon the tops of the beams and supporting the slabs and loads carried thereby, filler-retaining members extending over the tops of the beams and bridging the gaps between the ends of the slabs, and fills 15 of cementitious material in the spaces between the ends of the slabs above the tops of the beams.
2. A preformed building slab comprising a body of cementitious material, slab supporting and side facing bars molded in the sides of the slab and having their ends projecting beyond the ends of the slab, and integral cementitious flanges formed below said bars and extending laterally of the slab 25 whereby to form grout spaces when two of said slabs are in side abutting position.
3. A slab floor or roof comprising a plurality of spaced beams, preformed slabs extending between said beams and provided 30 with longitudinally extending slab supporting and side facing bars molded in the sides of the slabs and having their ends projecting beyond the ends of the slabs whereby to rest upon the tops of the beams to support 35 the slabs and loads carried thereby, integral cementitious flanges formed below said bars and extending longitudinally of the slabs to form a grout space between adjacent slabs, and grout retaining means under the ends of 40 the slabs extending over the tops of the beams and bridging the gaps between the ends of the slabs, whereby when grout is poured into the spaces between the slabs seepage of the grout out of said spaces will be substantially 45 avoided.
4. A preformed building slab comprising a body of cementitious material, channel bars forming supports and side facing for said slab, the flanges of said channel bars extending inwardly of the slab and providing corner reinforcement therefor, and anchoring strips welded at their ends to the under side of the lower flanges of the channel bars to connect said bars together.
5. A slab floor or roof, comprising a plurality of spaced beams, preformed, elongated, cementitious members extending between said beams and provided with a longitudinally extending bar having the ends of said bar projecting beyond the ends of the cementitious members and resting upon the tops of said beams and supporting the cementitious members and loads carried thereby, filler-retaining members extending over 60 the tops of said beams and bridging the gaps

between the ends of the cementitious members and slabs, and poured fills of cementitious material in the spaces between the ends of the cementitious members above the tops of the beams.

6. A slab floor or roof comprising a plurality of spaced beams, preformed slabs extending between said beams and provided with longitudinally extending slab-supporting and side-facing bars molded in the sides of the slabs and having their ends projecting beyond the ends of the slabs whereby to rest upon the tops of the beams to support the slabs and loads carried thereby, integral cementitious flanges formed below said bars and extending longitudinally of the slabs and outwardly from said slab, and grout-retaining means under the ends of the slabs and bridging the gaps between the ends of the slabs, whereby when a cementitious material is poured into the spaces between the slabs seepage of the cementitious material will be substantially avoided.

7. A preformed building slab comprising a body of cementitious material, slab-supporting and side-facing bars molded in the sides of the slab and having their ends projecting beyond the ends of the slab, and integral cementitious flanges formed below said bars and extending outwardly from the edges of the slab.

8. A preformed building slab comprising a body of cementitious material, slab-supporting and side-facing channel bars molded in the sides of the slab and having their ends projecting beyond the ends of the slab, integral cementitious flanges formed below said bars and extending outwardly from the edges of the slab, and a reinforcing member embedded in said slabs and extending between said bars.

9. As an article of manufacture, a composite slab comprising two spaced apart, metallic, structural members, each having a base, a set mass of plastic material between said members, the base of each element having set plastic material above and below the same, and integral flanges of the set plastic material extending outwardly from the edges of said slab below said base.

10. A preformed building slab comprising a body of cementitious material, channel bars forming supports and side facing for said slab, the flanges of said channel bars extending inwardly of the slab and providing corner reinforcement therefor, and anchoring strips embedded in said slab adjacent the lower flanges of said channel bars and serving to span the distance between said bars.

11. In a floor construction, a plurality of preformed cementitious building slabs arranged in a plane, a pair of structural bars molded into opposite edges of each slab at a substantial distance above the bottom faces

of the slabs, the ends of said bars extending beyond the ends of said slabs, spaced, structural beams engaging the ends of the bars so as to support said slabs, integral, outwardly extending, cementitious flanges formed on opposite edges of each slab below said bars, and a cementitious body above said flanges and connecting said slabs.

In testimony whereof, I sign my name.
